J. C. PRICE, OF NEW PHILADELPHIA, OHIO.

Letters Patent No. 60,935, dated January 1, 1867.

IMPROVEMENT IN HOISTING-TACKLE.

The Schedule referred to in these Letters Patent and making part of the same.

TO ALL WHOM IT MAY CONCERN:

Be it known that I, J. C. PRICE, of New Philadelphia, in the county of Tuscarawas, and State of Ohio, have invented a new and improved Hoisting-Tackle; and I do hereby declare that the following is a full, clear, and exact description thereof, which will enable those skilled in the art to make and use the same, reference being had to the accompanying drawings, forming part of this specification, in which—

Figure 1 is a side view of my invention.

Figure 2, a transverse section of the same, taken in the line xx , fig. 1.

Similar letters of reference indicate corresponding parts.

This invention relates to a new and improved tackle for hoisting articles generally, such, for instance, as hay from wagons into the bays of barns, goods in warehouses, etc., etc. The object of the invention is to obtain a device for the purpose specified, which will admit of the articles being hoisted, and also conveyed, when in an elevated state, to the place where they are to be deposited.

A A represent two plates, which may be of metal, and have three wheels or pulleys, B B B', fitted between them, the upper two of which, B B, run on a rope or wire, C, which serves as a way or guide and is stretched taut over the spot where the articles are to be raised and stored. D is the hoisting-rope which works over the lower wheel, B'; and has a conical collar, E, upon it, and a ring, F, just above the collar, as shown in fig. 1. The article to be raised is attached to one end of this rope and the other end is attached to a windlass by which the article is hoisted. G is a clamp, composed of a curved bar, secured by a pin or pivot bolt, a, between the two plates A A. One arm of this clamp has a cord, H, attached to it which extends down within reach of the operator or attendant. This clamp, G, serves to hold the plates A and pulleys B B' in position on the rope C when the article is being elevated, the operator, by pulling on the cord H, causing the clamp G to bind against the rope C. When the article is nearly elevated, the conical collar E will come in contact with the lower end of the clamp G, the end which has the cord H attached, and throws up said end so that the clamp will not bind against the rope C; and the wheels or pulleys B B will then, under the pull on rope D, be moved on the rope C and the hoisted or elevated article be moved along over the spot where it is to be deposited. The ring F prevents the load descending, in consequence of catching against a lip, a, at the under side of the clamp, when the lower arm thereof is released, and it is designed to have the rope C slightly inclined so that the wheels or pulleys, B B, may pass back by their own gravity, the ring F catching against the lip a', when the clamp is in the position shown in red, fig. 1, the clamp assuming this position by virtue of its own gravity as soon as the operator ceases to pull on cord H.

This invention is capable of very general application for hoisting purposes, and will answer admirably well for elevating and moving hay in barns, merchandise in warehouses, and like purposes.

I claim as new, and desire to secure by Letters Patent—

The clamp G, in combination with the plates A A, wheels B B', ropes C D, collar E, and ring F, all arranged to operate in the manner substantially as and for the purpose described.
